W. LIVELY.

PUMP JACK.

APPLICATION FILED MAR. 26, 1918.

1,301,856.

Patented Apr. 29, 1919.

UNITED STATES PATENT OFFICE.

WILLIAM LIVELY, OF QUANAH, TEXAS.

PUMP-JACK.

1,301,856.

Specification of Letters Patent. Patented Apr. 29, 1919.

Application filed March 26, 1918. Serial No. 224,874.

To all whom it may concern:

Be it known that I, WILLIAM LIVELY, a citizen of the United States of America, residing at Quanah, in the county of Hardeman and State of Texas, have invented certain new and useful Improvements in Pump-Jacks, of which the following is a specification.

My invention relates to pump jacks and more particularly to double-acting pump jacks; and the object is to simplify the mechanism for operating pump jacks and to provide pump jacks which will operate with less friction and which will have fewer parts and so decrease the load which the power has to overcome. The advantage is that the pump jack can lift more water in proportion to the power required. Another advantage is that the stroke of the piston rods can be easily varied and by a simple adjustment the stroke may be increased four times the length of adjustment of the adjusting element. Other objects and advantages will be fully explained in the following description and the invention will be more particularly pointed out in the claims.

Reference is had to the accompanying drawings which form a part of this application.

Figure 1 is a front elevation of the pump-jack, showing the pump cylinder in broken section. Fig. 2 is a side elevation of the same. Fig. 3 is a detail plan view of the upper cross-head. Fig. 4 is a detail elevation of the same. Fig. 5 is a plan view of the lower cross-head.

Similar characters of reference are used to indicate the same parts throughout the several views.

The pump jack is provided with a base frame having cross-beams 1 and 2 and uprights 3. The bearings 4 for the power shaft 5 of the power wheel 6 are mounted on the beams 2 which may be of angle iron. A pinion 7 is mounted on the shaft 5 for driving the pump-actuating wheel 8. The shaft 9 of wheel 8 is journaled in bearings 10 which are attached to beams 2. An upright guide and bearing frame which is composed of four uprights 11 are attached to the beams 2. The beams on two sides are connected by angle iron bars 12. The bars 12 are braced by a flat bar 13, preferably of steel or iron. Bearings 14 are attached to the bar 13 for a walking beam 15 which is fulcrumed in these bearings 14.

Brackets 16 are attached to uprights 11 on the side next to the pump rods for guide rods 17. Cross heads 18 and 19 move vertically on the rods 17. The cross-head 19 60 operates the interior piston rod 20 and the cross head 18 operates the exterior piston rod 21. A stuffing box 22 is mounted on the cylinder cap 23 for the piston rod 21. A stuffing box 24 for the interior piston 65 rod 20 is carried by the cross head 18. The exterior piston rod is actuated by the cross-head 18 and this cross-head is actuated by the cranks 25. Pitman rods 26 are pivotally connected to the cranks 25 and to 70 the cross-heads 18. When the wheel 8 is driven the cross-heads 18 will be reciprocated. The walking beam 15 is actuated by the cross-heads 18. The cross-heads 18 have laterally projecting arms 28, and arms 29 75 which project horizontally inward. The arms 29 are connected by straps 30. The walking beam 15 is operatively connected to arm 28 by a rod 31 which projects through a slot in the arm 28 and a pin 32 80 makes the connection. The upper end of the rod 31 is pivotally connected to the walking beam 15. The interior piston rod 20 is operatively connected to the walking beam 15. The exterior piston rod 21 is 85 connected to the arm 28 by a nut 33 and by the stuffing box 24. The interior piston rod 20 projects through the projection 34 on cross-head 19 and is held in operative relation thereto by nuts 35' and 36' and 37. 90 The rod 20 is thus compelled to move vertically by the cross-head 19 and the cross-head 19 is provided with lugs 35. A connecting rod 36 is pivotally connected to the walking beam 15 and pivotally connected 95 to the lugs 35.

The wheel 8 actuates the cross heads 18 and 19 by means of the pitman rods 26 and cranks 25. The pitman rods 26 are adjustably connected to the cranks 25 so that the 100 stroke can be varied. The pitman rods 26 are pivotally connected to depending lugs 38 on the cross-head 18. As the wheel 8 moves the cross-head 18 upwardly, there is an upstroke of the exterior piston rod 21. 105 At the same time, the cross-head 18 drives the connecting rod 31 upwardly and moves the walking beam 15 up on that side of the machine. This action forces the rod 36 downwardly and so forces the cross-head 19 110 downwardly simultaneously with the movement of the cross-head 18 upwardly and the

cross-head 19 causes a down-stroke of the interior piston rod 20 simultaneously with the up-stroke of the exterior piston rod 21 and vice versa. The piston rods 20 and 21 are thus reciprocated vertically in opposite directions by the single drive wheel 8.

What I claim is:

1. A pump jack for double-acting pumps comprising a frame, a power wheel and an actuating wheel provided with a shaft journaled in said frame, exterior and interior piston rods, a vertically reciprocating cross head for said interior pump rod, and a vertically reciprocating cross head for said exterior pump rod, cranks rigid with said shaft and pitman rods connecting said cranks to said lower cross-head, and operative connections whereby said actuating wheel reciprocates both cross heads in opposite directions simultaneously.

2. In a double acting pump jack provided with a frame and exterior and interior piston rods, an upper cross head for said interior piston rod, and a lower cross head for said exterior piston rod, a single actuating wheel provided with a shaft journaled in said frame, a pair of cranks rigid with said shaft and a pair of pitman rods connected to said cranks and to said lower cross-head for reciprocating said lower cross head vertically in said frame, a walking beam fulcrumed on said frame, means connecting one end of said walking beam to said lower cross head, and means connecting the other end of said beam to said upper cross head whereby said piston rods

are moved vertically in opposite directions simultaneously.

3. In a double acting pump jack provided with a frame and exterior and interior pump rods, a pair of cross heads one of which is connected to said exterior piston rod and an upper cross head connected to said interior pump rod, a walking beam fulcrumed on said frame with one end connected to the other lower cross head and the other end connected to said upper cross head, two pairs of vertical guide rods for said lower cross heads rigid with said frame and an actuating wheel operatively connected to said lower cross heads for reciprocating said upper and lower cross heads in opposite directions simultaneously.

4. In a double acting pump jack provided with a frame and exterior and interior pump rods, a walking beam fulcrumed on said frame, a lower cross head connected to said exterior pump rod and a lower cross head connected to said walking beam, means for making said cross-heads rigid with each other, vertical guide rods for said cross heads rigid with said frame, an upper cross head, means connecting said upper cross head to said walking beam, an actuating wheel provided with a shaft journaled in said frame, cranks rigid with said shaft, and pitman rods connecting said cranks to said lower cross-heads.

In testimony whereof, I set my hand, this 2nd day of March, A. D., 1918.

WILLIAM LIVELY.
